(57) **CLAIM**

The ornamental design for a net type atomizer, as shown and described.

DESCRIPTION

FIG. 1 is a top perspective view of a net type atomizer showing our new design;

FIG. 2 is another top perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right view thereof;

FIG. 8 is a top view thereof; and,

FIG. 9 is a bottom view thereof.

The broken lines in the drawings depict portions of the net type atomizer that form no part of the claimed design.

1 Claim, 9 Drawing Sheets
